(57) CLAIM

The ornamental design for a set of stackable cups, as shown and described.

DESCRIPTION

FIG. 1 is a perspective view of a set of stackable cups of our new design;

FIG. 2 is a front elevation thereof;

FIG. 3 is a rear elevation thereof;

FIG. 4 is a right side elevation thereof;

FIG. 5 is a left side elevation thereof;

FIG. 6 is a top plan view thereof;

FIG. 7 is a bottom plan view thereof;

FIG. 8 is a perspective view of a single cup assembly shown removed from the set of stackable cups of FIG. 1;

FIG. 9 is a front elevation thereof;

FIG. 10 is a rear elevation thereof;

FIG. 11 is a right side elevation thereof;

FIG. 12 is a left side elevation thereof;

FIG. 13 is a top plan view thereof; and,

FIG. 14 is a bottom plan view thereof.

In the drawings, the broken lines form no part of the claimed design.
